(74) Attorney, Agent, or Firm — Alexander Chen, Esq.

(57) **CLAIM**

The ornamental design for an arcade apparatus having a crane, as shown and described.

DESCRIPTION

FIG. 1 is a perspective view of an arcade apparatus having a crane;

FIG. 2 is a front view thereof;

FIG. 3 is a right side view thereof;

FIG. 4 is a left side view thereof; and,

FIG. 5 is a top view thereof.

The broken lines in the drawings depict portions of the arcade apparatus having a crane that form no part of the claimed design.
